UNITED STATES PATENT OFFICE.

WILLIAM E. PUTNAM, OF WESTON, MASSACHUSETTS.

UNTWISTING DEVICE.

Application filed June 2, 1922. Serial No. 565,414.

To all whom it may concern:

Be it known that I, WILLIAM E. PUTNAM, a citizen of the United States of America, and resident of Weston, in the county of 5 Middlesex and State of Massachusetts, have invented new and useful Improvements in Untwisting Devices, of which the following is a specification.

This invention relates to untwisting devices particularly adapted for use on portable electrical instruments such as telephone instruments which have a conductor cord carrying the electrical connections thereto. This cord has a tendency to become twisted 10 thereby shortening the cord, interfering with the movement of the instrument, and sometimes causing breakage of the conducting wires. The invention herein disclosed is in the nature of an alternative structure 15 or further adaptation of the inventive idea generically claimed in my copending application, Serial No. 565,413, filed on even date herewith.

One object of the invention is to provide 20 a portable electrical instrument which when lifted will automatically rotate to untwist its cord.

For a complete disclosure of the invention 25 reference will now be had to the drawings, in which,—

Fig. 1 is a side elevational view;

Fig. 2 is a rear elevational view;

Fig. 3 is a section on the line 3—3 of 30 Fig. 2;

Fig. 4 is a section on the line 4—4 of 35 Fig. 2;

Fig. 5 is an enlarged detail elevational 40 view of a modification; and

Fig. 6 is a section on the line 6—6 of 45 Fig. 5.

The embodiment of the invention shown 50 for the purpose of illustration comprises a portable telephone instrument of usual form comprising a base A, standard B, mouth piece C, and receiver D suspended from the standard B by the usual hook E. A cord F enters the base A of the instrument to make the electrical connections to the mouth piece and the receiver.

55 Since the cord F tends to become twisted during the use of the instrument suitable mechanism is provided for causing the instrument automatically to rotate to untwist the cord. This mechanism may take the form of a guide member G preferably tubular in form attached to the standard B of

the instrument by suitable spring clamp members H used in pairs as indicated in Fig. 3, and retained in clamping engagement with standard B and member G by 60 screws I. The guide member G is adapted to receive in telescopic relation therewithin a shaft J having spiral parallel grooves K extending longitudinally thereof and a handle L at its upper end. Means 65 which may take the form of pins or lugs M fast in the upper end of guide member G enter grooves K as indicated in Fig. 4 and cause members J and G to rotate relatively to each other when shaft J is caused 70 to move into or out of the guide member G. From this it follows that when handle L is utilized to lift the instrument the threaded connection between parts J and G and the weight of the instrument causes the 75 latter to rotate about shaft J as it moves downwardly under the influence of the force of gravity, thus untwisting cord F. When the instrument is returned to a support, shaft J on handle L returns by gravity to 80 its telescoped position within guide member G or may be forced back by pressing upon the top of the handle.

An extensive inspection of the cords to 85 portable telephone instruments discloses that the cords always twist in one direction so that one direction of rotation for such instruments is sufficient to untwist the cord. In certain cases, however, it may be 90 desirable or necessary to have the instrument rotate in the opposite direction. For this purpose a modified apparatus is disclosed in Figs. 5 and 6, in which spiral grooves N and N' are disposed in one direction of rotation and grooves O and O' in 95 the other direction of rotation upon a shaft J', similar in all respects to shaft J.

To provide a convenient means for changing the direction of rotation of the instrument when elevated in the manner described 100 guide member G' in Figs. 5 and 6 has a spanner P of spring material fast thereto as by rivets Q, the free ends of the spanner member P being provided with the lugs R and R', the former shaped to fit grooves 105 N and N' and the latter shaped to fit grooves O and O'. A button S having a shank S' extends through slot T in guide member G' and a similar slot in spanner member P and is headed over at S' against the 110 spanner. By sliding a button S to the right as shown in Figs. 5 and 6 lug R which is

out of contact with shaft J', will be released when the button is above rivets Q to permit it to drop into slot N' and as the button is moved farther it will retract lug R' from the slot O' so that the relative rotative movement of guide member G' mounted to shaft J' will be reversed from that shown in the drawings. The method of operating the modified structure is the same as that 10 for operating the form first described.

I claim:

1. In combination, a portable electrical instrument having a cord making the electrical connections thereto, and means causing said instrument to rotate automatically 15 when lifted vertically thereby.

2. In combination, a portable telephone instrument having a cord making the electrical connections thereto, a handle attached to said instrument, and means causing rotation of said instrument about a longitudinal axis when the instrument is 20 lifted vertically by said handle.

3. In combination, a portable telephone instrument having a cord making the electrical connections thereto, a handle attached to said instrument, and adjustable means causing rotation of said instrument about a longitudinal axis in either direction when 25 the instrument is lifted vertically by said handle.

4. In combination, a portable telephone instrument having a cord making the electrical connections thereto, a handle having a shaft attached thereto, and means connecting said handle through its shaft to said instrument and arranged to cause the latter to rotate substantially about said shaft, when the instrument is lifted vertically by 30 said handle.

5. In combination, a portable telephone instrument having a cord making the electrical connections thereto, a handle having a spirally threaded shaft fast thereon, and means attached to said instrument and arranged to cooperate with said shaft to cause said instrument when lifted vertically by 35 said handle to rotate around the shaft thereof.

50 6. In combination, a portable telephone instrument having a cord attached thereto, guide means on said instrument, an elongate member having a handle, and cooperating parts on said means and said member where- 55 by said instrument is caused to rotate about the axis of said member when lifted vertically by said handle.

7. In combination, a portable telephone instrument having a cord attached thereto,

a guide member on said instrument, an 60 elongate member adapted to telescope within said guide member, and cooperating parts of said members to cause said instrument to rotate about the axis of said members upon relative longitudinal movement thereof. 65

8. In combination, a portable telephone instrument having a cord attached thereto, a tubular guide member attached to said instrument, a handle having a spirally threaded shaft adapted to telescope within said 70 member, and means on said member engaging the spiral thread on said shaft whereby when said instrument is lifted vertically by said handle the former is caused by gravity to rotate about said shaft. 75

9. In combination, a portable telephone instrument having a cord attached thereto, a tubular guide member attached to said instrument, a handle having a spirally threaded shaft adapted to telescope within 80 said member, and adjustable means on said member engaging the spiral threads on said shaft whereby when said instrument is lifted vertically by said handle the former is caused by gravity to rotate in either direction around said shaft. 85

10. In combination, an instrument having a cord attached thereto, a guide on the instrument, a handle telescoping with the guide and having a right and left hand spirally grooved portion, and means on the guide alternately engageable with the right hand or left hand groove to control the direction of rotation of the instrument when 90 it is lifted vertically by the handle. 95

11. In combination, an instrument having a cord attached thereto, a tubular guide member attached to the instrument, a handle having a shaft provided with right and left hand spiral grooves, and spring pressed 100 members on the guide for engagement in the grooves, the guide having means for holding one of said members out of engagement with its groove.

12. In combination, an instrument having a cord attached thereto, a tubular guide member attached to the instrument, a handle having a shaft provided with right and left hand spiral grooves, and spring pressed 105 members on the guide for engagement in the grooves, and a shiftable member on the guide adapted to be moved to hold one or the other of said members out of engagement with the shaft. 110

Signed by me at Boston, Mass., this 31st 115 day of May 1922.

WILLIAM E. PUTNAM.
